TRIMMING MACHINE

George Hazelton, Leicester, England, assignor to
 United Shoe Machinery Corporation, Paterson,
 N. J., a corporation of New Jersey

Application October 30, 1934, Serial No. 750,686
 In Great Britain November 29, 1933

16 Claims. (Cl. 12—85)

This invention relates to trimming machines and is illustrated as embodied in a machine for trimming the laterally projecting margins of heel-breast covering flaps.

5 In the manufacture of shoes it is usual to trim the laterally projecting margins of a heel-breast covering flap which is split from the sole of a shoe, flush with the respective breast edges of the heel of the shoe. Such an operation may 10 be performed by the use of a hand tool or may be carried out in a machine such, for example, as that disclosed in United States Letters Patent No. 1,708,401, granted April 9, 1929, upon an application filed in the names of Ricks & Woodcock.

15 In the manufacture of shoes having Louis heels however, it is desirable to provide heel-breast covering flaps having "Viennese" edges which in the finished shoe extend slightly beyond the breast edges of the heel and are rounded. Before the lateral edges of the heel-breast covering flap are rounded by a burnishing tool it is necessary to trim the laterally projecting margins so that they extend just beyond the respective breast edges of the heel. Moreover, in 25 order to facilitate the formation of a rounded edge it is desirable that opposite sides of the slightly projecting portion of the trimmed flap be beveled.

30 The trimming of the projecting lateral portions of heel-breast covering flaps to the desired width and shape preparatory to burnishing or otherwise finishing the same may be performed by hand. While satisfactory results may be achieved by hand trimming and finishing, such operations are slow and care must be taken to insure that both edge faces of the flap are trimmed and finished alike. Moreover, such operation requires the services of a skilled operator.

35 With the above-mentioned circumstances in view and in accordance with a feature of this invention there is provided spaced gages constructed and arranged to engage opposite sides of a piece of flexible sheet material, and cutters which are movable in paths disposed at substantial angles to each other for trimming material guided past the cutters by said gages with intersecting beveling cuts. The illustrated construction is described with reference to trimming the 40 projecting lateral margins of a heel-breast covering flap cemented to a heel, the work-guiding mechanism comprising a pair of spaced gages one of which engages a side of the heel adjacent to a breast edge beyond which the heel-breast covering flap projects and the other of 45 which engages the covered breast of the heel adjacent to the breast edge. The cutters which trim the projecting lateral margins of the heel-breast covering flap travel in intersecting paths 50 and each is moved across the path of cutting 55

movement of the other alternately to trim surplus material from such margins with a pair of beveling cuts thus forming a V-shaped edge face which projects beyond the breast edge of the heel.

5 With the above construction the projecting margins of heel-breast covering flaps attached to heels may be quickly and effectively trimmed to provide V-shaped edge faces which project laterally of corresponding breast edges of the heel.

These and other features of the invention including certain details of construction and combination of parts will be described as embodied in an illustrated machine and pointed out in the appended claims.

Referring now to the accompanying drawings, Fig. 1 is a side view of the illustrated machine, a side cover of which has been removed to show cutter-operating mechanism of the machine; 20

Fig. 2 is an enlarged side elevation of the portion of the machine to which work is presented;

Fig. 3 is a front elevation of a portion of the machine as viewed along line III—III of Fig. 2;

Fig. 4 is a view showing in perspective trimming 25 knives and gages of the illustrated machine during the trimming of one of the projecting margins of a heel-breast covering flap which has been cemented to the breast of a heel;

Fig. 5 is an enlarged sectional view of a heel 30 before a projecting margin of its heel-breast covering flap has been trimmed;

Fig. 6 is a view showing the machine in the process of trimming the projecting margin of the flap illustrated in Fig. 5;

Fig. 7 is a view showing the edge face of the flap after it has been trimmed by the illustrated machine;

Fig. 8 is a view of a portion of the heel the heel-breast covering flap of which is in the process of having its edge face rounded by one form of edge-setting tool;

Figs. 9, 10, 11 and 12 illustrate heel-breast 45 covering flaps having edge faces of various shapes;

Fig. 13 is a sectional view taken along the line XIII—XIII of Fig. 1;

Fig. 14 shows a side view of the operating head of the machine provided with modified work-positioning gages;

Fig. 15 is a front elevation of the machine illustrated in Fig. 14; and

Fig. 16 is a side view of a modified work gage of the machine.

55 The illustrated machine is described with reference to trimming the projecting lateral margins 20 (Fig. 5) of covers or heel-breast covering flaps 22 which have been cemented to the breasts of heels 24, with a pair of beveling cuts, thereby 60

to provide a V-shaped edge face comprising a pair of beveled surfaces 26 (Fig. 7) which intersect to form a ridge 28 (Figs. 4 and 7) and project laterally of a corresponding breast edge 30. 5 The V-shaped edge face is then molded to a predetermined shape by a suitable edge setting or burnishing tool 32 (Fig. 8) to provide a projecting rounded edge face 34 which is referred to as a Viennese edge. The shape of the finished edge 10 face may be varied in accordance with the shape of the edge-setting tool to provide Viennese edges 36, 38, 40 and 41, such as illustrated in Figs. 9, 10, 11 and 12, respectively.

In order to trim the projecting lateral margins 15 of the heel-breast covering flap to provide the V-shaped edge face illustrated in Fig. 7, the illustrated machine is provided with a pair of cutters or knives 42 and 44 mounted for reciprocation in intersecting paths, each of the knives being 20 moved across the path of movement of the other alternately, and a pair of spaced gages 46, 48 for engaging the side and the breast faces 50 and 52 of the heel respectively, adjacent to the breast edge 30 (Fig. 5) beyond which the margin 25 20 of the heel-breast covering flap projects, in order to guide the heel 24 and the projecting margin 20 past the knives 42 and 44. It will thus be noted that the cutters are mounted for movement in paths intersecting each other approximately midway between the sides or side faces 29 and 31 (Fig. 5) of the projecting lateral margin 20 of the heel-breast covering flap 22.

In the illustrated trimming machine the trimming knives 42, 44 are arranged for reciprocation 35 in paths inclined at an angle of 90° to each other and are inclined at about 45° to the horizontal. The knives 42, 44 are similarly formed and their cutting edges 54 and 56, respectively, are laterally curved as illustrated in Fig. 4 in order to facilitate trimming along a sharply curved part of 40 the breast edge 30 of the heel 24. The knife 42 is secured to the lower end of a carrier 58 mounted in a guideway 60 which is formed in the machine frame, the knife being secured to the carrier 45 by a screw 62 which is in threaded relation with the carrier 58 and passes through an elongated slot in the knife so that the latter may be initially adjusted relatively to the carrier. The carrier 58 is reciprocated along its guideway 50 60 by an eccentric 64 (Fig. 1) keyed to the end of a horizontal shaft (not shown) which is rotatably mounted in the machine frame and is rotated by a pulley 61 driven by a belt 63. The eccentric 64 is housed within an inner race 65 of a ball bearing the outer race 66 of which engages faces 55 68 and 70 of the carrier 58. The face 68 forms part of the bottom of an opening extending laterally through the carrier 58, and the face 70 is formed on the lower end of a block 72 which may be adjusted relatively to the carrier 58 in order 60 to position the block lengthwise of the carrier. To compensate for wear of the faces 68 and 70 and of the outer race 66, the block 72 may be moved to adjusted position relatively to the ball bearing by the provision of a screw 74 in threaded relation with the carrier 58 and engaging the block 72. The screw 74 carries a lock-nut 76 for securing it in proper adjusted position.

The upper end of the carrier 58 is provided with 70 an extension 78 which is connected by a dumb-bell shaped member 80 to an arm 82 of a bell-crank lever 84. The bell-crank lever is secured on a stud 85 (Fig. 13) rotatably and slidably mounted in the machine frame. A head 86 on 75 the stud 85 against which the lever is clamped by

a nut 87 is held by a spring 89 against a face 91 on the machine frame. The spring 89 bears against the bottom of a recess in the machine frame and against a collar secured to the stud 85. The spring 89 takes up the wear between 5 the head 86 and the frame. The stud 85 is secured in the main frame at substantially the same level as the point where the paths of movement of the trimming knives 42 and 44 intersect. The arm 82 of the bell-crank lever 84 extends downwardly and rearwardly from its connection with the dumb-bell member 80 at an angle of approximately 45° to the horizontal. A lower arm 90 10 of the bell-crank lever 84 extends forwardly and downwardly from the stud 85 at an angle of approximately 45° and is connected by a second dumb-bell member 92 to the lower end of a carrier 100 to which the knife 44 is secured by a screw 102. The carrier 100 is mounted in a guideway 104 of the machine frame and extends 15 upwardly and forwardly at an angle of about 45°. The dumb-bell shaped members 80, 92 are both alike and have at their ends rectangular blocks 106, 108, respectively, which are clamped in circular bores in the carriers and the arms of the 20 bell-crank lever. The carrier 58 and the arm 82 are split to receive the blocks 106, respectively, which are held within the circular bores of these members by screws 110. The carrier 100 and the arm 90 are also split for the reception of the 25 blocks 108 which are held in place within the bores of these members, respectively, by screws 111. The rectangular blocks 106, 108 are joined by comparatively thin shank portions which may 30 bend slightly laterally as the carriers 58, 100 move 35 in rectilinear paths and the bell-crank lever 84 pivots about the stud 85. In order to obtain as much lateral flexibility of the dumb-bell shaped members 80, 92 as possible while retaining sufficient strength lengthwise to actuate the carriers 40 58, 100 the dumb-bell shaped members may be divided lengthwise, the thin portion being divided into two still thinner and more flexible portions.

The heel 24 and the heel-breast covering flap 45 22 are guided by the gages or guides 46, 48 as they are fed by the operator past the knives 42, 44. The gage 46 is secured by a screw 112 to the machine frame, which screw passes through a slot 114 in the gage so that the same may be 50 adjusted in directions indicated by arrows 116 (Fig. 2). The gage 46 may be pivotally adjusted about the screw 112 by means of two adjusting screws 117, 118 which are in threaded relation with lugs 120 and 122, respectively, extending 55 from the frame and are constructed and arranged to engage a flange 124 (Figs. 2 and 3) projecting from the gage. The gage 46 may be clamped in adjusted position by setting up on the adjusting screws 112, 117 and 118.

The upper face 126 (Fig. 4) of the gage 46 near its convex heel-engaging face 125 is somewhat rounded to conform to the lateral curvature of the cutting edge 54 of the knife 42 and the knife may be so adjusted on the carrier 58 that when 65 the knife descends its cutting edge 54 just contacts with the upper surface 126 of the gage 46 to insure that a clean cut is made through the margin of the heel-breast covering flap 22. Although the knife 42 is described as engaging the 70 upper surface 126 of the gage 46, the knife may be so arranged that it cooperates with the upper rounded edge of the heel-engaging face 125 of the gage 46 to form a shearing couple. By rounding the heel-engaging face 125 of the gage 46 the 75

feeding of the work past the knives 42, 44 is facilitated. The under side of the gage 46 is provided with a concavity 128 to provide clearance for the upper of the shoe as the trimming progresses along the upper part of the heel breast.

The gage 48 is secured to the frame by a screw 130 which passes through a slot 132 in the gage and is in threaded engagement with the machine frame so that the gage may be conveniently adjusted in directions indicated by arrows 134, the gage being provided with a tongue 136 which enters a groove 138 in the machine frame and prevents the gage from twisting about the screw 130. The upper surface 140 (Figs. 2 and 4) of the gage 48 is concave to conform to the transverse curvature of the under side of the knife 44. The flap-engaging face 142 (Fig. 6) of the gage 48 is convex and provides a smooth surface against which the heel-breast covering flap 22 cemented to the heel 24 bears and by which it is braced as it is fed past the knives 42, 44. The knife 44 passes through the projecting margin 20 just above the upper surface 140 of the gage 48.

The machine frame when viewed from the side (Fig. 1) is substantially in the form of a square with one of its corners uppermost and having extending downwardly from it a base 144 which may be secured to a work bench (not shown). The square portion of the frame is hollowed out at the center to provide clearance for the fore-part of the shoe when the heel-breast flap is presented to and fed past the knives 42, 44. The frame is comparatively narrow so that no part of it interferes with the manipulation of the shoe. The bell-crank lever 84 is housed within the frame of the machine, a cover 146 (Fig. 3) corresponding in shape to the frame being secured to the side of the same by screws 148.

The knives 42, 44 are reciprocated at high speeds, the shaft upon which the eccentric 64 is mounted being driven at a speed of about 4,000 revolutions per minute, the knives reciprocating in the same vertical plane. The knives 42, 44 move toward the projecting margin 20 of the heel-breast covering flap alternatively and it is desirable that there should be as little slackness as possible in the connections of the mechanism which operate the carriers 58, 100 so that the knives may be moved a definite distance to and fro and in order that the wear of the parts and the noise are eliminated as far as practicable. Particularly it is desirable in the case of the carrier 58 that the knife 42 shall have a definite movement because, as previously stated, the knife when it moves downwardly just engages the upper face 126 of the gage 46. The construction of the machine is such that its desirable result is as far as possible achieved since wear between the outer race 66 and the faces 68 and 70 with which it engages can be compensated for by adjustment of the block 72 as above described. Moreover, the stud 85 upon which the bell-crank lever 84 is mounted can be adjusted to take up any wear between the stud and the bell-crank lever.

It will be noted as illustrated in Fig. 7 that the beveled faces 26 which form the ridge 28 are of equal sizes and are disposed at the same angle to the general plane of the flap. By previously forming a V-shaped face at a lateral margin of the flap, the rounded face 34 (Fig. 8) may be quickly formed by the edge-setting tool 32. It is sometimes common to form heel-breast covering flaps having projecting edge faces such as illustrated in Figs. 9 and 10, 11 and 12, respec-

tively, which faces are formed by suitably shaped tools after providing the flap with V-shaped edge faces of the proper shape.

The finishing of the V-shaped edge faces after they have been trimmed by the illustrated machine may be conveniently effected in a machine having an oscillating burnishing tool with a work-engaging groove of the desired shape. A machine suitable for finishing the edges of heel-breast covering flaps after they have been trimmed as above described may be in the nature of the attachment which is disclosed in United States Letters Patent No. 2,000,961, granted May 14, 1935 on an application filed in the name of Keall and is provided with a suitably formed tool. The edge-finishing machine is preferably provided with means whereby during the operation of the heel-breast covering cap the amount of oscillation of the tool can be varied by the operator so that when operating around a comparatively sharply curved part of the edge of the flap the amount of oscillation of the tool may be smaller than when operating along a comparatively straight part.

Figs. 14 and 15 illustrate a machine similar to that above disclosed but having slightly modified work-positioning gages. Knives 146 and 148 are operated by mechanism similar to that for operating the knives 42 and 44, respectively, the heel being guided past the knives by gages 150 and 152. The gage 150 is secured by a screw 154 to the main frame. The screw 154 has formed on it a flange 156 which engages the gage 150. The screw 154 passes through an opening 157 in the gage which is constructed and arranged to allow the gage to be adjusted upwardly and downwardly. The gage 150 is secured by a screw 158 to a rod 160 adjustably mounted in a block 162. The rod 160 is threaded at its upper end and has threaded on it a nut 164 which is held by a spring 166 against the block 162. By adjusting the nut 164 the gage 150 may be adjusted vertically, upwardly and downwardly. The block 162 has extended from it a stem 168 slidably mounted in the machine frame and adjustable, by means of a nut 170 threaded on its upper end, parallel to the path of movement of a slide 172 to which the knife 148 is attached. The upper end of the stem 168 is provided with a recess of suitable size to receive a spring 174 the upper end of which is in engagement with an upper face 175 of the opening. It will thus be clear that the nut 170 is held against the lower face 171 of the opening by the spring 174 and that the block 162 may be adjusted lengthwise of the path of movement of the slide 172 by turning the nut 170. The springs 166, 174 are strong enough to prevent upward movement of the guide 150 by pressure of work against it. By means of the nut 164 the guide 150 may be adjusted vertically relatively to the edge of the knife 146 to vary the distance which the edge of the trimmed flap projects beyond the side of the heel and by means of the nut 170 the gage 150 may be adjusted to vary the position laterally of the flap of the apex of the angles of the cuts made by the knives. This latter adjustment will necessitate adjustment of the knife 146 so that it just engages the gage 150 and also the adjustment of the gage 152 to suit the thickness of the flap. Since breast flaps are usually comparatively thin and it is contemplated that the amount the breast flap projects beyond the side of the heel will in any case be small, the adjustment of the gage 150 above described will not be large and in any position of adjustment of the gage the knife 148 will pass over the tip of the gage.

Means are provided whereby the gage 152 may be quickly adjusted to suit the thickness of the breast flap. It is desirable that the space between the gages 150, 152 shall be such that the flap will just pass between them but that the gauges will control the edge of the flap. Since a change in thickness may occur in two consecutive flaps presented to the machine or even in the same flap it is desirable that that adjustment can be quickly made.

The gage 152 is made in two parts 176, 178 connected together by a right and left-hand threaded screw 180 having on it a collar 182. The part 178 of the gage 152 is secured to the frame by a screw 184 which passes through a slot in the part 178 and the part 178 has on it a tongue which enters a groove in the frame. The part 176 of the gage 152 has on it a tongue which enters the same groove as the tongue on the part 178. The tongue on the part 176 is held in a groove by a screw 186 which passes through a slot in the part 176. The screw 186 does not clamp the part 176 to the machine frame, but allows such part to move upwardly or downwardly towards or from the gage 150 when either the screw 182 is rotated or when the screw 184 is slackened and the two parts 176, 178 are moved bodily on the frame towards or from the gage 150. The part 178 has adjustably mounted on it two screws 188 which are arranged to be engaged by the collar 182 when the screw 180 is adjusted to move the part 176 towards or from the gage 150. The screws 188 may be so adjusted that the screw 180 may be quickly rotated to adjust the part 176 from one predetermined position to another, which positions can be adjusted by means of screws 188 to suit the variation in the thickness of the breast flap. The adjustment may, however, be made irrespective of the positions of the screws 188 which may be used as limit stops to prevent over-adjustment of the part 176.

The gage 152 is shaped so that the breast flap below the edge which is being trimmed may be held against it and this part of the guide controls the angle of the cuts in relation to the flap. If it is desired to trim a flap in which the angles of the cuts are, for instance as illustrated in Fig. 12, a different part 176 will be used instead of the part shown in Fig. 14 so that the heel can be tilted and the trimming knife caused to trim the edge to the desired angles. To obtain the shape of the edge shown in Fig. 12 it will be necessary to adjust the gage 150 slightly. The knife 148 passes through the material just above the upper surface of the gage 150.

In order to reduce the reshaping of the edge face of the cover by the edge setting tool 32 to a minimum it is desirable that the beveled surfaces shall approximate as nearly as practicable the shape of the edge face of the breast cover of the finished shoe. Accordingly the gages 46 and 48 as well as the gages 150, 152 are constructed and arranged to permit the operator to dispose the projecting margins of the breast cover at various angles to the paths of movement of the knives 146, 148.

It is desirable that the gage which engages the side of the heel shall be adjusted lengthwise of the paths of movement of the knives 146, 148, respectively. Accordingly, as illustrated in Fig. 16 of the drawings, a gage 190 is clamped by a set screw 192 to the main frame, the gage being provided with an elongated opening 194. The opening 194 is arranged in parallel relation with the path of movement of the knife 148. A

rod 196 is secured to the gage 190 and passes through a recess formed in a boss 198. The recess through which the rod 196 passes is arranged in parallel relation with the path of movement of the knife 148. A spring 200 is positioned between the boss 198 and the lower enlarged end of the rod 196, the upper end of which is in threaded relation with an adjusting nut 202. The block 198 is provided with a stem 204 constructed and arranged to slide in a recess 206 of the main frame. The recess is arranged in parallel relation with the path of movement of the knife 146. The stem 204 may be adjusted along the recess 206 by a nut similar to the nut 170 illustrated in Fig. 14. In view of the foregoing it will be clear that the gage 190 may be adjusted lengthwise of the path of movement of the cutter 148 by releasing the set screw 192 and turning the nut 202, and may be adjusted lengthwise of the path of movement of the cutter 146 by sliding the stem 204 along the recess 206.

Having described my invention, what I claim as new and desire to secure by Letters Patent of the United States is:

1. In a trimming machine, spaced gages constructed and arranged to engage opposite sides of a piece of flexible sheet material, and cutters movable in paths disposed at substantial angles to each other for trimming material guided past the cutters by said gages thereby to trim the material with intersecting beveling cuts.

2. In a trimming machine, spaced guide members constructed and arranged to engage the opposite side faces of a piece of flexible sheet material, and cutters provided with laterally curved cutting edges respectively mounted for movement in paths intersecting each other between the side faces of the material guided past the cutters by said gages thereby to trim the material with intersecting beveling cuts.

3. In a trimming machine, spaced guide members constructed and arranged to engage the opposite side faces of a piece of flexible sheet material, cutters mounted for movement in paths intersecting each other between the side faces of the material guided past the cutters by said gages thereby to trim the material with intersecting beveling cuts.

4. In a trimming machine, means for guiding a heel a margin of the attached cover of which projects beyond the heel, and cutters arranged for movement in angularly disposed paths intersecting each other between the opposite side faces of the projecting margin of the cover of the heel guided past said cutters to trim said margin to a predetermined width with beveling cuts.

5. In a trimming machine, means for guiding a heel a margin of the attached cover of which projects beyond the heel, cutters arranged for movement in angularly disposed paths intersecting each other between the opposite side faces of the projecting margin of the cover of the heel guided past said cutters, and mechanism for moving each of the cutters across the path of movement of the other alternately to trim said margin to a predetermined width with beveling cuts.

6. In a trimming machine, spaced guide members constructed and arranged to engage the

opposite sides of a piece of flexible sheet material, and cutters constructed and arranged each to enter one side of the material at spaced points and to progress along fixed paths to the opposite side of the material, said paths being arranged to intersect each other between the sides of the material guided by said members past the cutters thereby to trim a portion of the material with intersecting beveling cuts.

5 10. A trimming machine having, in combination, a gage for engaging a side of a heel provided with a breast cover a lateral margin of which projects beyond a breast edge of the heel, a gage for engaging the covered breast of the heel, said gages being spaced to form an opening for receiving said projecting margin and constructed and arranged to brace the said margin, and cutters for trimming the projecting margin guided past the cutters and braced by said gages with a pair of intersecting cuts thereby to form a V-shaped margin which extends slightly laterally of the breast edge of the heel.

15 11. A trimming machine having, in combination, a gage for engaging a side of a heel provided with a breast cover a lateral margin of which projects beyond a breast edge of the heel, a gage for engaging the covered breast of the heel, said gages being arranged to engage the heel adjacent to said breast edge and spaced to provide an opening for receiving said margin, and cutters mounted for movement in paths which are disposed in angular relation and intersect each other between the opposite side faces of the projecting margin of the breast cover guided by said gages 20 thereby to form a trimmed flap lateral edges of which are provided with a pair of beveled faces inclined to each other.

25 12. In a machine for trimming a projecting margin of a cover attached to a heel, a pair of gages provided with convex heel engaging surfaces spaced from each other to provide an opening for receiving the projecting margin, and a pair of knives movable in angularly disposed paths intersecting each other approximately midway between the sides of said projecting margin thereby 30 to bevel said margin with a pair of intersecting cuts.

35 13. In a trimming machine, a gage provided with a work engaging face, a knife provided with a cutting edge movable in a fixed path, means for operating the knife to cause the cutting edge to move substantially into engagement with said face, a second gage spaced from the first named gage and provided with a work engaging face, and a second knife movable in a fixed path which 40 extends beyond the working face of the second gage and is inclined at a substantial angle to the path of movement of the first-named knife.

45 14. In a trimming machine, a gage provided with a work engaging face, a knife provided with a cutting edge movable in a fixed path, means for operating the knife to cause said cutting edge to move substantially into engagement with said face, a second gage spaced from the first-named gage and provided with a work engaging face, and a second knife movable in a fixed path which extends beyond the work engaging face of the second gage and is inclined at a substantial angle to and intersects the path of movement of the first-named knife.

50 15. In a trimming machine, a gage provided with a work engaging face, a knife provided with a cutting edge movable in a fixed path, means for operating the knife to cause said cutting edge to move substantially into engagement with said face, a second gage spaced from the first-named gage and provided with a work engaging face, and a second knife movable in a fixed path which 55 extends beyond the working face of the second gage and is inclined at a substantial angle to the path of movement of the first-named knife.

55 16. In a trimming machine, a gage provided with a work engaging face, a knife provided with a cutting edge movable in a fixed path, means for operating the knife to cause said cutting edge to move substantially into engagement with said face, a second gage spaced from the first-named gage and provided with a work engaging face, and a second knife movable in a fixed path which 60 extends beyond the work engaging face of the second gage and is inclined at a substantial angle to and intersects the path of movement of the first-named knife.

65 17. In a trimming machine, a gage provided with a work engaging face, a knife provided with a cutting edge movable in a fixed path, means for operating the knife to cause said cutting edge to move substantially into engagement with said face, a second gage spaced from the first-named gage and provided with a work engaging face, and a second knife movable in a fixed path which 65 extends beyond the work engaging face of the second gage and is inclined at a substantial angle to and intersects the path of movement of the first-named knife.

70 18. In a trimming machine, a gage provided with a convex work engaging face, a knife movable in a fixed path and having a cutting edge which is laterally curved in accordance with the curvature of said face, means for operating the knife to cause said cutting edge to move substantially into engagement with said face, a second gage spaced from the first-named gage and provided with a convex work engaging face, a second knife provided with a laterally curved cutting edge and movable in a path which extends beyond the work engaging face of the second gage and is inclined at a substantial angle to and extends beyond the path of movement of the first-named knife, and mechanism for operating the knives.

75 19. In a trimming machine, a gage provided with a convex work engaging face terminating in a curved edge, a knife movable in a fixed path and having a cutting edge which is laterally curved in accordance with the curvature of said edge of the gage, means for operating the knife to cause its cutting edge to move substantially into engagement with said edge of the gage, a second gage spaced from the first named gage and provided with a convex work engaging face, a second knife provided with a laterally curved cutting edge movable in a path which extends beyond the work engaging face of the second gage and is inclined at a substantial angle to and intersects the path of movement of the first named knife, and mechanism for alternately operating each of the knives 80 across the path of movement of the other knife.

20 21. A trimming machine comprising a pair of gages constructed and arranged to engage angularly disposed faces of a heel a margin of an attached cover of which projects beyond the heel, said gages being spaced to provide an opening for said projecting margin of the cover, and a pair of cutters movable in paths disposed at substantial angles to each other and constructed and arranged to trim the projecting margins to a predetermined width with a pair of beveling cuts disposed in angular relation to each other.

25 22. In a trimming machine, a pair of cutters provided with cutting edges portions of which are movable in fixed intersecting paths included in a single plane for trimming the projecting margin of a cover attached to a heel, spaced gages constructed and arranged to engage simultaneously angularly disposed surfaces of the heel for guiding the heel and the projecting margin past the cutters, and mechanism for alternately moving each of the cutters across the path of movement of the other to trim the projecting margin with a pair of beveling cuts.

30 23. In a trimming machine, means for guiding and bracing a projecting margin of a cover which is attached to a heel, a pair of cutter carriers, a cutter secured to each of the carriers, said cutter carriers being constructed and arranged for movement to cause the cutters to move in paths intersecting each other between opposite faces of the projecting margin of the cover of the heel guided past said cutters, a bell-crank lever, universal connections between opposite arms of the lever and the respective carriers, and mechanism for operating the carriers to cause the cutters to move alternately across the margin supported by said means thereby to trim the projecting margin to a predetermined width with a pair of beveling cuts.

35 24. GEORGE HAZELTON.
